(57) **CLAIM**

The ornamental design for a display screen or portion
thereof with graphical user interface, as shown and
described.

DESCRIPTION

A portion of the disclosure of this patent document contains
material to which a claim for copyright and trademark is
made. The copyright and trademark owner has no objection
to the reproduction of the patent document or the patent
disclosure, as it appears in the U.S. Patent Office records, but
reserves all other copyright and trademark rights whatsoever.

The patent or application file contains at least one drawing
executed in color. Copies of this patent or patent application
with color drawing(s) will be provided by the Office upon
request and payment of the necessary fee.

The sole FIGURE is a front view of a display screen or
portion thereof with graphical user interface showing our
new design.

The broken lines showing a display screen or portion
thereof, as well as the text, symbols and portions of the
graphical user interface illustrate portions of the article and
form no part of the claimed design.
